United States Patent Office

Des. 175,803
Patented Oct. 11, 1955

175,803

RECORD SUPPORT

Robert L. Smith, Mount Vernon, N. Y.

Application February 26, 1954, Serial No. 29,238

Term of patent 7 years

(Cl. D56—1)

Fig. 1.

Fig. 2.

Figure 1 is a side elevational view of a record support, showing my new design.

Figure 2 is a top plan view of the device, as shown in Figure 1.

I claim:

The ornamental design for a record support, as shown.
